UNITED STATES PATENT OFFICE.

WILLIAM H. HANSCOM, OF HAVERHILL, AND JOHN S. LARRABEE, OF LAWRENCE,
MASSACHUSETTS.

SANDPAPER-CUTTING MACHINE.

1,120,143.

Specification of Letters Patent.

Patented Dec. 8, 1914.

Application filed June 30, 1913. Serial No. 776,539.

To all whom it may concern:

Be it known that we, WILLIAM H. HANSCOM and JOHN S. LARRABEE, citizens of the United States, residing at Haverhill and at 5 Lawrence, respectively, in the county of Essex and Commonwealth of Massachusetts, have invented a new and useful Sandpaper-Cutting Machine, of which the following is a specification.

10 The object of our invention is to provide a novel paper cutting machine especially designed for cutting sand paper; to provide novel means for guiding and measuring the paper prior to cutting; to provide novel, adjustable and effective cutting mechanism; to provide in connection with the cutting mechanism novel means for securely holding the paper in position during the cutting operation; and to provide novel means for setting the paper guide and measuring mechanism for cutting either narrow or wide strips.

It is also an object of our invention to provide as the means for holding the paper an automatic device so arranged that it will always grip the paper when the cutting operation is in progress and release the paper when the knife is raised.

A further object of our invention is to provide a novel combination and arrangement of parts to afford greater convenience and effectiveness of operation in a machine of this character.

We attain these objects by the mechanism illustrated in the accompanying drawings, which form a part of this specification, and in which—

Figure 1 is a top plan of the entire machine; Fig. 2 is a front view showing the 40 arrangement of the rolls and with the knife in raised position; Fig. 3 is a side view of the entire machine showing the knife lowered as it completes the cutting operation; Fig. 4 is a vertical section of the knife blades, knife holder and bed of the machine; Fig. 5 is a detail cross sectional view of the upper knife and means for adjusting it.

Like characters of reference indicate like parts throughout the several views.

50 Our sand paper cutting machine has a bed 1, provided with roll supports 2, the latter

having recessed portions 3, in which are removably mounted roll-holding rods 4, which support rolls of sand paper indicated by the letter S. Secured to opposite sides of the 55 bed 1, there are provided side plates 6, in which are mounted a paper guide rod 5 extending across the bed of the machine to guide the paper as it is unrolled.

The paper cutting mechanism comprises 60 a lower knife 20, secured to bed 1, having its cutting edge substantially in alignment with the bed, as illustrated in Fig. 4, and an upper knife, 9, secured to a knife holder 7 and thus pivotally mounted by means of 65 knife-head piece 8 to knife bracket 29, which is secured to the side of the bed 1, as shown. Knife 20 has a transversely diagonal concave edge surface 21, and knife 9 has a similar transversely diagonal concave edge surface 10. The transversely diagonal concave knife edges prevent the grit from crushing under the knives during the cutting operation. As a means for adjusting the lower knife 20 we provide adjusting 75 screws 22; and for adjusting the upper knife 9, we provide adjusting screws 23, in order that the knives may be so adjusted as to prevent the paper from wedging in between them and so that they will cut a smooth and 80 straight edge. Upper knife 9 is fastened to knife holder 7 by screws 24.

Automatic paper-holding mechanism is provided for holding the paper during the cutting operation and releasing it when the 85 upper knife 9 is raised at the conclusion of the cutting off of a strip. This mechanism comprises one or more presser feet 12, slidably mounted in a suitable presser foot holder 11, the latter member being adjustably mounted on the knife holder 7, as shown in the drawings. Presser feet 12 are yieldingly held in their lowest or normal position by springs 13, arranged preferably as 90 illustrated.

Paper measuring mechanism is provided for measuring strips of suitable width to be cut from the roll. Rules 26 are provided, mounted in the bed 1 of the machine and positioned preferably as illustrated in Fig. 1, 100 or otherwise suitably positioned for use in connection with our measuring member 19,

which is provided at its ends with toothed bars or racks 18, adapted to engage with corresponding pinions 17, mounted on a suitable rod 14, and which is supported by 5 rod supports 28, suitably secured to the bed or side plates of the machine, as illustrated in the drawings. Rod 14 is provided at one of its ends with hand wheel 15, as illustrated in Fig. 1, and at the reverse end with locking nut 16. When it is desired to measure off wide instead of narrow strips of sand paper for cutting, we may also provide supports 27, positioned substantially as illustrated in Figs. 1 and 3. It is also within the 10 contemplation of our invention to arrange or construct rod supports 28 so as to be removably secured to the bed of the machine in both the position they occupy in the drawings and in the position occupied by supports 27, for convenience in changing the 15 position of measuring member 19 and the means for operating it, according as narrow or wide strips are desired. Rod supports 28 may be of any suitable construction, their 20 primary function being to support rod 14.

25 indicates a recess extending across the bed of the machine, for the upper knife 9 and knife holder 7 to operate in during the cutting operation, as illustrated in Fig. 3. 30 Provision is made for the holding of a plurality of sand paper rolls in roll supports 2 in order that different kinds or grades of sand paper may be conveniently available, as, for example, #80 grit, #70 grit and 35 #120 grit.

In operation, the end of a roll of sandpaper is unwound, drawn under guide rod 5, and its edge brought into abutment against measuring member 19, which, operated by 40 hand wheel 15, rod 14, pinions 17 and racks 18, may be set at the desired distance on rule 26 from the fixed lower knife 20. The upper knife 9, secured to knife holder 7, which has been raised, is then brought down with a 45 cross shearing motion which gives a good clean cut, the transversely diagonal concave ground cutting surfaces of both knife blades avoiding the crushing of grit on the paper, and making an effective cutting mechanism 50 for the purpose intended. As the knife enters the paper, the presser foot (or presser feet, successively, as the case may be) presses upon the paper and holds it firmly during the cutting operation, and releases the paper 55 when the upper knife is again raised. The springs 13, as will be understood from the drawings, give the desired tension to the presser foot 12, which is slideable in presser foot holder 11.

60 The measuring member 19 when in the position illustrated in Fig. 1 is capable of adjustment to and from the edge of lower knife 20, sufficiently for measuring narrow strips, and when it is desired to cut wide

strips it is operated from the supports 27. 65 Locking nut 16, as will be understood from the drawings, serves to fasten the measuring member 19 in a fixed position when desired. When desired, the locking nut may be unscrewed, rod 14 withdrawn from rod supports 28 and the mechanism assembled in operative position mounted in supports 27, the latter having a like function to that of rod supports 28.

It is understood that it is within the contemplation of our invention to cast parts integrally or separate, as may be desired; and we preferably provide a frame or bed with knife holder bracket and rod supports cast 70 as one.

It is within the contemplation of our invention to reverse the positioning of the knife blades and knife holding members relative to the bed members to which they are attached. It is also within the contemplation of our invention to reverse the positioning of the roll supports to the opposite or reverse side of the machine. It is further within the contemplation of our invention to reverse the positioning of the measuring 85 members to the opposite bed of the machine from that shown in the drawings. It is essential that the presser foot mechanism be spaced substantially apart from the cutting edge of the knife blades at the point of its 90 contact with the sandpaper, whereby the sandpaper is arched over the concave edge surface of the lower knife blade and the paper held against slipping as herein set forth. It is also essential for sandpaper cutting 95 that the blades have concave diagonal edge surfaces to avoid dulling.

What we claim is:

1. In a machine of the class described, the combination of means for supporting one or 100 more sand-paper rolls, cutting mechanism comprising an adjustable stationary knife and an adjustable swinging knife, and means adjustably mounted on the knife 105 holder for yieldingly pressing down upon the sand paper during the cutting operation and releasing the pressure when the swinging 110 knife is raised, the aforesaid means being positioned to press upon the sand paper at portions spaced substantially apart from the 115 edge of the blade to arch the sandpaper over the knife edge surface, whereby to prevent the sandpaper from dulling the knife blade.

2. In a sand paper cutting machine, the combination with a paper cutting machine 120 of measuring mechanism comprising a bed having one or more rules, a measuring member 125 slideable on the bed and disposed parallel with the cutting mechanism, to form an abutting surface for the edge of the sand paper, toothed bars mounted on the ends of the measuring member, said bars being of a length substantially equal to the width of

the measuring member, pinions meshing with the aforesaid bars, a rod on which the pinions are mounted, supports for the rod, a hand wheel secured to the rod at one end for adjusting the measuring mechanism in the desired position, and a locking nut at the opposite end of the rod for locking the measuring mechanism in any desired position.

3. In a sand paper cutting machine, the combination of a bed, means mounted thereon for holding one or more sand paper rolls, a stationary knife blade, means for its lateral oblique adjustment and attachment to the bed of the machine in substantial alignment therewith, and a swinging knife pivotally attached to the bed and having an obliquely adjustable blade member, the blade members having concave edge surfaces, whereby sandpaper may be severed with the least possible dulling of cutting edges.

4. In a machine of the class described, the combination of a bed, an obliquely-adjustable stationary lower knife secured to the bed, a knife holder pivotally mounted to one side of the bed, an obliquely adjustable upper knife mounted in the knife holder, the aforesaid knives having concave edge surfaces and being diagonally shaped to provide a cutting mechanism with non-parallel surfaces to prevent crushing of grit, and resilient paper-holding mechanism adjustably mounted on the machine and positioned to engage the paper at points spaced substantially apart from the knife blade.

5. In a machine of the class described, the combination of a bed, means for holding one or more rolls of paper mounted thereon, an obliquely positioned lower knife having a transversely diagonal concave edge surface, means for securing the aforesaid knife to the bed of the machine and for its oblique lateral adjustment, a knife holder mounted at one side of the bed of the machine, an obliquely adjustable upper knife having a transversely diagonal concave edge surface mounted in the knife holder, means for attaching the upper knife to the holder and for its oblique lateral adjustment, and paper-holding means engageable with the sand paper at points spaced substantially apart from the cutting edge of the knives and arranged to operate only during the cutting operation.

6. In a machine of the class described, the combination of a bed, means for holding one or more rolls of paper mounted thereon, a stationary laterally adjustable lower knife secured to the bed of the machine, a radially-movable knife holder mounted on the bed of the machine and having a laterally adjustable upper knife secured thereto, the aforesaid knives being shaped and posi-

tioned to coöperate in cutting sand paper without crushing the grit, means for guiding the paper prior to the cutting operation, means including a fixed rule and a movable measuring member and rack and pinion actuating mechanism for measuring strips of any desired width to be severed from a roll, means for adjusting the aforesaid measuring means, and a plurality of sets of opposite supports positioned in spaced relation relative to the knife mechanism, for the purposes specified.

7. In combination with a paper cutting machine of the character described, a pivotally mounted knife holder and upper knife having one or more automatic paper-holding mechanisms adjustably secured to the knife holder, comprising a presser foot holder, a presser foot member vertically slidable in the aforesaid holder and spaced substantially apart from the knife blade, and resilient means attached to the presser foot holder and presser foot member for yieldingly pressing the presser foot member downward to engage with and hold the strip of paper to be severed during the cutting operation, the presser foot being positioned to contact with the paper at a point beyond the edge surface of a lower knife blade to arch the paper and obviate dulling of the knife edge.

8. In a machine of the class described, the combination of means for supporting a plurality of sand paper rolls, a bed having a recess extending across the machine through which narrow sand paper strips may fall when severed, paper-measuring members on the bed of the machine, an obliquely-positioned adjustable lower knife blade secured to the recessed portion of the bed, a swinging upper knife having an obliquely-adjustable knife blade mounted thereon, and adjustably-mounted, yielding presser foot mechanism spaced substantially apart from said upper knife blade to hold the sandpaper during the cutting operation in position to prevent rubbing of grit on the edge of the knife blades, substantially as set forth.

9. In a sand paper cutting machine, the combination of a bed having a recess extending across the machine through which sand paper strips may fall when severed, means for measuring the paper strips on the bed of the machine prior to cutting, means for holding one or more rolls of paper on the machine, an obliquely-adjustable lower knife blade adjustably attached to the recessed portion of the bed, a pivotally-swinging knife holder having an obliquely adjustable upper knife blade adjustably attached thereto, said knife blade being tapered to cut a smooth edge and prevent

- crushing of grit, and yielding presser foot mechanism longitudinally adjustable relative to the knife holder and removed from the cutting edge of the knife to contact with the sandpaper at a point or points at such distance from the cutting edge as to prevent grit from dulling the knives.

In testimony whereof we affix our signatures.

WILLIAM H. HANSCOM.
